UNITED STATES PATENT OFFICE.

CHARLES MULDNER, OF CLEVELAND, OHIO.

CARPET-RENOVATOR.

SPECIFICATION forming part of Letters Patent No. 267,917, dated November 21, 1882.

Application filed June 16, 1882. (No model.)

To all whom it may concern:

Be it known that I, CHARLES MULDNER, of Cleveland, in the county of Cuyahoga and State of Ohio, have invented a certain new and Improved Carpet-Renovator; and I do hereby declare that the following is a full, clear, and complete description thereof.

The nature of my invention relates to a carpet-renovator; and it consists of a lagged or grated cylinder with openings between the said lags, and the interior provided with spiral longitudinal ribs or wings projecting from the interior surface of the cylinder. The cylinder is mounted in a frame upon journals, for its rotation by any suitable motor.

That the invention may be more fully understood, reference will be made to the following specification and to the annexed drawings, making part of the same, in which—

Figure 1 is a side view, and Fig. 2 a transverse vertical section in the direction of the line *xx*, Fig. 1.

Like letters refer to like parts in the several views.

The frame A may be of any suitable construction for the purpose of supporting the grated cylinder B, which cylinder is made up of lags and two solid or entire heads, C C, to which are securely connected the journals or gudgeons D D, Fig. 1, to one of which are attached the driving-pulley E and loose pulley F, provided with a belt for rotating and stopping the cylinder. To the periphery of the heads are secured the lags G, with a space, H, between for the escape of dust and dirt from the agitated carpet. Thus the entire circle of the cylinder is made up of lags with intervening spaces. In the interior of the cylinder, and secured to the inside face, are ribs or wings I I".

These ribs may project more or less from the interior face of the cylinder in radial lines, as seen in Fig. 2, and they may be arranged to be in alignment with the cylinder, or in a diagonal or spiral line, as indicated at I' I", Fig. 2, and by the dotted lines I' I" in Fig. 1. The spiral or diagonal positions of the ribs I' I" are arranged in opposite directions, for a purpose hereinafter set forth. The entrance to the interior is through a door, J, which is hinged at K K and provided with a removable

fastening at L, Fig. 1. By means of this door the carpets are placed in and withdrawn from the cylinder. The grated cylinder may be revolved in either direction for the purpose designed, and during its revolutions, when the carpet is within, it is carried up by the ribs to a point where it will slide off and fall down on the ribs below, which ribs again will convey the loose carpet to the point above, from which it will slip off the rib to fall down onto the ribs below. In this way the loose carpet, by the rotation of the cylinder, is constantly being carried up by the wings or ribs and as constantly sliding off and falling back. This operation of raising up the carpet and of its falling back is as continuous as the rotation of the cylinder. By means of the oblique or diagonal position of the wings I' the carpet is conveyed in a lateral direction while it is being agitated by the rotation of the cylinder and wings. The wings I' I" are placed in the interior of the cylinder in such relation to each other that one of the said wings or ribs, I', will cause the carpet to be directed longitudinally in the cylinder in one direction, while the other wing, I", will cause the carpet to be moved laterally in an opposite direction. By this means the carpet is subjected to compound movement by the action of the wings I and lateral or longitudinal movement caused by the ribs I' I". In this way a continuous agitation and beating of the carpet is maintained, thus causing the carpet to be constantly unfolding, and exposing it in all parts to the renovating and cleaning action of the ribs as they revolve. The cylinder is designed to be from ten to fifteen feet in diameter, more or less, as may be required for the work.

The falling and rolling motion of the carpet from the wings as they rise onto those below produces an action not unlike that of shaking and beating out the dust and dirt, so as to completely renovate it without tearing or other injury. The dirt and dust, as it escapes from the carpet, passes away out of the cylinder through the spaces between the lags, and is accelerated by the wings in the cylinder, which act as rotary fans in driving out the dust as fast as it is removed from the carpet. In this way the wings have a purpose—that of agit-

ing and renovating the carpet, and also for fanning or driving out the dust from the cylinder.

What I claim as my invention, and desire to secure by Letters Patent, is—

5 In carpet cleaning machines, the grated cylinder B, having axial journals connected with the heads thereof, for its rotation in suitable frame-work, in combination with a series of wings extending from and diagonally across

the entire interior face of the cylinder in opposite directions to each other, and provided with a door opening into said cylinder.

In testimony whereof I affix my signature in presence of two witnesses.

CHARLES MULDNER.
